UNITED STATES PATENT OFFICE.

PAUL M. KUEHN, OF BALTIMORE, MARYLAND, ASSIGNOR TO THE BARTLETT HAYWARD COMPANY, OF BALTIMORE, MARYLAND, A CORPORATION OF MARYLAND.

SHAKING-SCREEN.

1,159,317.

Specification of Letters Patent.

Patented Nov. 2, 1915.

Application filed April 2, 1914. Serial No. 828,949.

To all whom it may concern:

Be it known that I, PAUL M. KUEHN, a citizen of the United States, residing at Baltimore, in the State of Maryland, have 5 invented certain new and useful Improvements in Shaking-Screens, of which the following is a specification.

This invention relates to improvements in shaking screens and has more particularly 10 reference to screens of considerable weight.

One object of the invention is to provide a rigid supporting structure between which the screen or screens may be sustained in an improved manner preferably with one 15 screen-end overlapping another screen-end—the sustaining means having yielding buffers to take the shock during the shifting movement of the screens from one direction to another.

20 Another object of the invention is to provide an improved arrangement of buffers distributed between the supporting structure and the screen or screens so that the strains caused by the shifting of the screen 25 or screens will be distributed over the supporting structure at numerous points and racking of the apparatus will be avoided.

With these and other objects in view the invention is illustrated in the accompanying 30 drawings, wherein,

Figures 1 and 1^a, illustrate the structural metal side supports and the screens in top plan. Figs. 2 and 2^a, show side supports in side elevation. Fig. 3, illustrates the screen 35 structure in end elevation. Fig. 4, shows on an enlarged scale the lapped screens in side elevation and also shows the sustaining means and a portion of the side supporting structure. Figs. 5 and 6, illustrate front

40 face and side or edge elevations respectively of one of the hanger arms. Fig. 7, shows a detail on an enlarged scale of a portion of the screen bottom and side wall and one of the suspension spindles. Fig. 8, illustrates 45 the shaft which imparts a reciprocating-motion to the screens. Fig. 9, shows an enlarged sectional detail through one of the rods which pivotally sustains the buffer rods, and Fig. 10, illustrates a cross-sectional detail 50 through one of the buffer bars. Fig. 11, shows a modified form of buffer, and Fig. 12 illustrates an end view of the spring shown in Fig. 11.

Referring to the drawings the numeral, 55 11, designates two parallel side metal gird-

ers, constructed in a strong and rigid manner and preferably connected by cross-bars, 12, which serve to tie the same together. The vertical wall, 13, of each supporting girder is provided with a series of bearing 60 brackets, 14,—the brackets being so disposed in the two vertical girder-walls that a rod, 15, may extend horizontally across the girders at each bracket and have one end sustained in a bracket on one girder and its 65 other end sustained in another bracket directly opposite and on the other girder. It is therefore to be understood that there will be as many rods, 15, extending horizontally between the girders as there are bracket- 70 bearings on either of the said girders.

Each rod, 15, pivotally sustains two hanger arms, 16,—one arm being on the rod at the inner side of and adjacent to one girder support, and the other arm being on 75 the same rod adjacent to the inner side of the other girder support. Each hanger arm, as shown particularly in Figs. 5 and 6 of the drawings, is stamped up from heavy metal with a central longitudinal rib, 17, and two 80 side flanges, 18. The ends of each hanger arm are folded back and riveted at, 19, to the flanges, 18, and each fold is formed into an eye so that each hanger will have an eye, 20, at one end and another eye, 21, at the 85 opposite end and a bushing, 22, is provided in each hanger eye. The hanger-eyes, 20, receive the ends of rods, 15, which latter form the pivot from which said hangers depend. The longitudinal rib, 17, of each hanger arm 90 is provided with a slot, 23, located preferably adjacent to the eye, 21, which latter in practice is the lower eye, as will presently be more fully explained.

In so far as construction is concerned the 95 bearing brackets 14, rods, 15, and hanger arms, 16, are alike throughout the device, but by reference to Figs. 2, 2^a, and 4, of the drawings, it will be seen that at one end of the machine the bearing brackets are positioned lower down on the vertical wall of the girder supports than those bearing brackets at the opposite end of the machine. This is due to the fact that in the present instance two screen frames, 24, and, 25, respectively are employed in the machine and screen frame, 24, is somewhat lower than screen frame, 25, and in order to utilize the same length of hanger arm throughout the machine, those bearing brackets which sus- 100 105 110

tain the rods that carry the hangers for the lower screen frame are somewhat lower on the girder than the brackets from which the higher screen frame are hung.

5 The screen frames are of substantially the same construction and a description of one is deemed sufficient. Each screen-frame has two longitudinal side walls, 26, and a bottom, 27. The bottom of each screen is provided with a number of perforations, 28, which latter are arranged in groups, each group differing in size and becoming larger according to their distance from the receiving end of the screen. At intervals the two 10 side walls of the screen-frames are connected at their upper sides by cross-bars, 29, while at the lower or bottom side each screen frame has a series of crosswise angle bars, 30, extending horizontally between and connecting the side walls. The outer end of each angle-bar, 30, carries an arm, 31, with a spindle, 32, at the outer projecting end thereof, as best seen in Fig. 7, of the drawing, so that along the bottom and at both 15 sides of each screen frame there will be a series of spindles which project toward the inner side of the supporting girder wall. The locations of these spindles with respect to the lower ends of the hanger arms are 20 such that each spindle will engage or extend through the bushing, 22, of an eye, 21, of a hanger arm so that the screen frame will be pivotally sustained from and swing between the pendant hanger arms at opposite sides. 25 30 35 From the foregoing explanation it will be seen that the upper ends of the hanger arms, 16, are pivotally sustained from the horizontal cross-rods, 15, and hang pendants from said rods at the inner sides of the supporting side girders; that the screen frames 40 extend longitudinally between the girders and have position between the pendant hanger arms at opposite sides and that the lower ends of the said hanger arms are 45 pivotally engaged by spindles which extend horizontally from the under side of the screen frames and thereby sustain the screen frames.

The screen frames are to be oscillated by 50 means presently to be described and to take up the shock at the end of each oscillating stroke I have provided an improved arrangement of yielding buffers, which will now be described, attention being directed more 55 particularly to Figs. 4, 5, and 9, of the drawings.

It has heretofore been pointed out that the hanger arms, 16, are provided with a slot, 23, adjacent to their lower ends, and by reference to Figs. 2, 2^a, and 4, it will be seen that some of the hanger arms coact with buffer rods, 33, which latter extend through the hanger arm slots, 23, and have eyes, 34. These buffer rods have an inclined position 60 65 with respect to the screen frames and hanger

arms and the eye-ends thereof extend below the bottom of the screen with which they coact. Suitable horizontal rods, 35, extend crosswise between the girders and below the screen frame and said rods are so located 70 as to extend through the eyes of two buffer rods at directly opposite sides of the screen frame. In order to hold the buffer rod eyes properly on the rods, 35, the latter are provided with tubular spacing sleeves, 36, and, 75 37. The sleeves, 36, are interposed between the eye of a rod and the inner side of the girder adjacent thereto and the sleeve, 37, is located on the rod, 35, between two buffer rod eyes so that lateral movement of the eyes 80 on the rod, 35, will be prevented.

Each buffer rod, 35, has an adjusting nut, 38, thereon between the eye and the hanger arm, and a coiled spring, 39, encircles said rod, 35, and is interposed between the said 85 adjusting nut, 38, and the rear side of the hanger arm. On the upper free end of the rods, 35, I provide coiled springs, 40, which have one end seated against the front side of the hanger arms and their other ends held 90 by seating against adjusting nuts, 41, on the extreme end of the rods. It will therefore be seen that by extending the buffer rods through the hanger arms and providing a buffer spring, 39, and, 40, on opposite sides 95 of the arms, and then pivotally sustaining one end of each buffer rod, I provide a yielding buffer on each side of the said arms, one of which buffers checks the movement of the arms as they swing the screen frame in 100 one direction, and the other buffer will check the movement of said arms when they swing the screen frame in a reverse direction. It will also be noted that the free ends of the buffer rods, 33, will rock as the hanger arms 105 swing but that longitudinal movement of the rods will be prevented by reason of their pivot attachment to the horizontal rods, 35.

By referring to Fig. 4 of the drawing it will be noted that the inner ends of the two 110 screen frames, 24, and, 25, lap,—the lower and foremost screen frame, 24, underlapping the higher and rearmost screen frame, 25. It will also be noted that the higher overlapping end of the screen frame, 25, carries a pivoted flap, 42, whose lower free end rests upon the upper side of the lower screen frame to close the space between said lapsing frames and prevent the material that is being screened from working back 115 between the screens.

A shaft, 43, is sustained in suitable bearings, 44, at opposite sides of the machine and has two sets of crank arms, 45, and, 46, respectively thereon. Two connecting rods, 125 47, extend from the crank arms, 45, back to and engage the screen frame, 25, while two other connecting rods, 48, extend forwardly from the crank arms, 46, and connect with the screen frame, 24. The relative positions 130

of the crank arms, 45, and, 46, are such that the screen frames will be reciprocated toward and from each other and by means of the hanger arms the motion imparted to the 5 screens will be through an arc instead of a direct reciprocation so that the advance of the material will be somewhat retarded and at the same time tumbled so as to effect a turning of the materials during the screening 10 and enable the smaller particles to work under the mass and discharge through the smaller openings.

Motion is imparted to the shaft, 43, by means of a pulley, 49, which is driven by a 15 belt, 50, from a motor, 51, or other power means.

In Fig. 11, a modified form of hanger arm buffer is shown which consists of a threaded rod, 52, extending through the hanger arm, 20 53, with adjusting nuts, 53, and, 54, on opposite sides of said arm. This rod has a head, 55, with an exterior circumferential spiral groove, 56, therein so that one end of a spiral spring, 57, may engage the head by 25 means of said groove. The other end of the spring, 57, engages a spiral groove, 59, on an eye-block, 60, and said block has an eye, 61, through which the cross-rods, 35, will extend. By means of this construction the 30 springs, 57, will compress as the screens and arms approach the limit of movement in one direction and thereby check the screens and when moved in a reverse direction the springs must be expanded to allow the 35 screens to make their full stroke and thereby check the movement on this reverse stroke.

Having thus described my invention what I claim and desire to secure by Letters Patent is:—

40 1. In a shaking screen the combination with a supporting means, of a plurality of pivoted devices carried by the supporting means; a screen pivotally connected to said pivoted devices; means for reciprocating the

screen; means in the path of the pivoted devices to retard their movement as they near the limit of movement in one direction, and means also in the path of said pivoted devices to retard the latter as they near the limit of movement in the other direction. 45 50

2. In a shaking screen the combination with a supporting means, of a plurality of hanger arms pivotally sustained by and depending from the supporting means; a screen pivotally sustained between said 55 hanger arms; means for reciprocating said screen and hanger arms and springs at opposite sides of some of said arms to retard their movement.

3. In a shaking screen the combination 60 with a supporting means, of a plurality of hanger arms pivotally sustained by and depending from the supporting means; a screen pivotally sustained between said 65 hanger arm; means for reciprocating said screen and hanger arms; a buffer rod extending through some of said hanger arms and a spring on the said buffer rod at opposite sides of the hanger arm.

4. In a shaking screen the combination 70 with a supporting means, of a plurality of hanger arms pivotally sustained by and depending from the supporting means; a screen pivotally sustained between said 75 hanger arms; means for reciprocating said screen and hanger arms; buffer rods having one end pivotally sustained with respect to the supporting means and their other ends engaging some of said hanger arms and springs on the buffer rods and engaging opposite sides of said hanger arms. 80

In testimony whereof I affix my signature in presence of two witnesses.

PAUL M. KUEHN.
